UNITED STATES PATENT OFFICE.

CHARLES H. BROWN, OF FLUSHING, NEW YORK.

SHOE.

Application filed July 13, 1922. Serial No. 574,705.

Among the principal objects which the present invention has in view are: to prevent shoes for personal wear bending or becoming flexible under the longitudinal or 5 long arch of the human foot; to decrease the weight of the material needed to insure the necessary rigidity of the above mentioned structure without diminishing the structural resistance thereof; to insure the stability of 10 the service relations of the parts of the structure above mentioned; to furnish means incorporated in the shoe structure for manipulating the metatarsal arch of the human foot when wearing a shoe of the character de- 15 scribed; to support the rear portion of the longitudinal arch adjacent the heel of the wearer; and to improve the construction of the shoe and particularly the so-called shank portion thereof.

20 *Drawings.*

Figure 1 is a side view partly in section of a shoe constructed and arranged in accordance with the present invention, the section being taken lengthwise thereof.

Figure 2 is a horizontal section taken on the line 2—2 in Figure 1, the superposed portions of the structure being cut away to disclose the arrangement of structural ele- 30 ments otherwise covered thereby.

Figure 3 is a cross section, the section being taken as on the line 3—3 in Figure 2.

Figure 4 is a section taken as on the line 4—4 in Figure 2.

35 Figure 5 is a detail view in perspective showing schematically the shank iron and parts associated therewith for manipulating the members of the metatarsal arch and for anchoring the iron in service relation to the 40 general shoe structure.

Description.

The present invention more specifically relates to an improvement on the structure dis- 45 closed in the Patent No. 1,249,318 issued to me under date of December 11, 1917, for improvements in shoes, to which patent cross reference is here made, and more partic- 50 ularly to the introductory portion of the speci- 55 fication thereof as contained in paragraphs 3, 4, 5 and 6, extending from lines 13 on page 1 of the specification in said patent, to line 55 on page 2 thereof.

As seen in the accompanying drawings the 55 shoe is rendered substantially rigid, between the sole 10 and heel 11 of the shoe, and more

particularly between the point indicated by the numeral 12 and the heel 11. The point in the shoe indicated by the numeral 12 is that corresponding with the inner joint of the great toe of the wearer, it being the purpose and intention that the shoe or sole 10 thereof, shall bend on the line coincident with the said joint. To this end a shank iron is provided with a horizontal inward 60 extension 13 and an inclined outer extension 14. These sections are seen best in Figures 2 and 3 of the drawings.

To strengthen the shank iron and to augment the resistance to any bending effort 70 offered by the inclined extension 14, I form a preferably pendent ridge 15. This construction permits me to use a lighter material in the construction of the shank iron than would otherwise suffice.

75 As disclosed in the patent above referred to, the shank iron is further provided with anchoring spurs 16 which enter the insole 17 and parts associated therewith to maintain the service disposition of the front end of the shank iron. At the rear extremity of the shank iron a perforation 18 is provided to receive a fastening member or members such as the tack 19.

By employing the spurs 16 and the tack 80 19, it is obvious the shank iron is securely held in the shoe structure.

It will be understood that the last em- 85 ployed in building shoes constructed and arranged in accordance with the present in- 90 vention, is preferably provided with a pocket or depressed portion adapted to receive the protuberance 20 molded in the insole 17. When molding the protuberance 20 in the insole 17, a recess is formed at the under side 95 thereof adapted to receive a pad 21 which is secured thereto by any suitable adhesives. When employing a canvas reinforcing cover 22, this is overlaid and secured to the insole 17 and the pad 21 in the manner shown best 100 in Figure 2 of the drawings. It will be understood, however, that the insole may be otherwise formed to provide a thickened area where the pad is shown in the present drawings.

105 It will be understood that when construct- 110 ing shoes in accordance with the present in- vention the insole is preliminarily molded to form the protuberance 20 with the pad 21 therein seated, and covered by the canvas cover 22.

The insole is applied to the last and is

2
structurally connected with the upper of the shoe, ready to receive the sole 10 before the shank iron is placed. The rearward edges of the pad 21 project slightly beyond the general level of the insole to form an abutment for the shoulders 23 on the shank iron which is formed at the forward terminal of the extensions 13 and 14 thereof. The shank iron is shaped to form the flat extension 24, at the edges of which are the spurs 16, as best seen in Figure 5 of the drawings.

Secured to the underside of the extension 24 is a skived tab 25, the edge whereof extends beyond the extension 24 and is connected to the insole and the canvas cover 22 thereof. Coincident with the attachment of the tab 25 with the insole above referred to, the spurs 16 are driven or imbedded in the pad 21 and insole 17, the iron having been properly located by means of the upstanding edge of the said pad 21 against which the shoulders 23 are abutted. The sole 10 is now overlaid upon the insole, and the shank iron, and to a welt provided therefor the said sole is secured.

It will be seen that coincident with the metatarsal arch of the foot, the present structure has provided an added thickness resting on the sole 10 embodying the tab 25, the extension 24 of the shank iron, the pad 21, and the protuberance 20 of the insole 17. When the foot is now placed in the shoe the flesh of the foot below the said arch rests directly upon the protuberance 20, and when the weight of the foot is thrown thereon as in walking, the pad serves to support the arch and to prevent the usual contraction thereof as when forced into a circular or gutterlike recess as results when wearing shoes of usual construction. As a direct result of this support the articulated bony structure forming the said arch is opened and caused to function, thereby promoting circulation of the blood in this portion of the foot.

It will be noted by reference to Figures 1 and 2 of the drawings that the inclined extension 14 of the shank iron terminates at a point forward of the breast of the heel 11. The shape of the heel of the wearer and the longitudinal arch carries on the inside of the foot back beyond the breast of the heel. It is to support the section of the longitudinal arch above the heel and back of the breast thereof that I insert the triangular pad 26 which is molded to correspond with the lift of the extension 14. It will be understood that the edges of the pad 26 are skived or cut away so that the surface pad fades or blends into the under surface of the insole so

as to avoid forming a ridge or wrinkle therein. The introduction of the pad 26 in the manner described serves to maintain the heel of the wearer properly placed in the shoe.

Claims.

1. In a shoe as characterized in combination an insole molded to form a projection extending upward in the shoe in the region of the metatarsal arch of the foot, a pad permanently attached to said insole beneath the molded section to support said molded section in service, the rear edge of said pad forming a substantial rearwardly opposed shoulder to conform with a shoulder of a shank iron for supporting said pad and insole, and a shank iron having at its forward end a relatively flat extension having rearwardly extending shoulders intersecting at an obtuse angle for registering said iron in relation to said pad and projection.

2. In a shoe as characterized in combination an insole molded to form a projection extending upward in the shoe in the region of the metatarsal arch of the foot, a pad permanently attached to said insole beneath the molded section to support said molded section in service, the rear edge of said pad forming a substantial rearwardly opposed shoulder to conform with a shoulder of a shank iron for supporting said pad and insole, a shank iron having at its forward end a relatively flat extension having rearwardly extending shoulders intersecting at an obtuse angle for registering said iron in relation to said pad and projection, and means provided in said extension for attaching the same to said pad and projection.

3. In a shoe as characterized in combination an insole molded to form a projection extending upward in the shoe in the region of the metatarsal arch of the foot, a pad permanently attached to said insole beneath the molded section to support said molded section in service, the rear edge of said pad forming a substantial rearwardly opposed shoulder to conform with a shoulder of a shank iron for supporting said pad and insole, a shank iron having at its forward end a relatively flat extension having rearwardly extending shoulders intersecting at an obtuse angle for registering said iron in relation to said pad and projection, and means provided in said extension for attaching the same to said pad and projection, said means embodying anchoring spurs upturned at the forward edge of said extension for insertion into said pad and insole structure.

CHARLES H. BROWN.
